DESIGN FOR A LIGHTING FIXTURE

Maurice W. Ross, Niles Center, and Edwin D. Tillson, Evanston, Ill.

Application March 23, 1936, Serial No. 61,743

Term of patent 14 years

To all whom it may concern:

Be it known that we, Maurice W. Ross and Edwin D. Tillson, both citizens of the United States, residing, respectively, at Niles Center, in the county of Cook and State of Illinois, and Evanston, in the county of Cook and State of Illinois, have invented a new, original, and ornamental Design for Lighting Fixture, of which the following is a specification, reference being had to the accompanying drawing, forming a part thereof.

We claim:

The ornamental design for a lighting fixture, as shown.

In witness whereof, I hereunto subscribe my name this 18th day of March, 1936.

MAURICE W. ROSS.

In witness whereof, I hereunto subscribe my name this 18th day of March, 1936.

EDWIN D. TILLSON.
